UNITED STATES PATENT OFFICE.

ROBERT F. CLARK, OF SALT LAKE CITY, UTAH.

COMBINATION COAL AND WOOD HEATING-STOVE.

1,223,768.

Specification of Letters Patent. Patented Apr. 24, 1917.

Application filed November 23, 1915. Serial No. 63,073.

To all whom it may concern:

Be it known that I, ROBERT F. CLARK, a citizen of the United States, and a resident of Salt Lake City, in the county of Salt Lake and State of Utah, have invented certain new and useful Improvements in a Combination Coal and Wood Heating-Stove, of which the following, together with the accompanying drawings, constitute a full, clear, and exact specification, which will enable others skilled in the art to which it pertains to make and use the same.

My invention relates to heating stoves and its objects are:

15 First. To provide a heating stove in which may be burned all the common grades and sizes of coal, and also ordinary fire-wood, all, with practically equal advantage.

Second. To obtain a maximum heating effect from the fuel consumed.

Third. To allow easy regulation and a more perfect control than can be attained in the ordinary heating stove.

I accomplish these objects, by constructing the lower portion of my stove with double walls having an air space between them; the inner wall being formed by a cast iron fire pot and the outer wall by a sheet metal body or shell which extends both above and below the fire pot. The horizontal cross-section of my stove is preferably made oval in shape and the fire pot has a lip or flange at its top which extends approximately two thirds of the distance from the front to the back of the stove on each side, and this lip or flange having a bearing against the shell forms the top closure for the space between the two walls. At the front of the stove is a closable inlet for admitting air from the atmosphere to the space between the two walls, and at the rear of the stove the said space opens upwardly into what I choose to call an "expansion chamber". This expansion chamber occupies, generally, about one third the area of the corresponding horizontal section of the stove, and the bounding surfaces of the expansion chamber give it somewhat the shape of a carpel of an orange, placed horizontally, with its curved face coinciding with the curved rear portion of the stove shell, and the two extremities of the carpel joining the extremities of the lip or flange

already mentioned. The lower inclined wall of the chamber is suitably perforated and its upper inclined wall is continuous, so that 55 a current of air striking the under side thereof will be deflected downwardly and through the perforations or ports in the lower inclined wall, into the fire.

One embodiment of my invention is illustrated in the accompanying drawings in which:

Figure 1, represents a horizontal section taken on the line 1—1 and partly on the line 1^a—1^a in Fig. 4 viewed from above; 60

Fig. 2, a fragmentary transverse vertical section on the line 2—2 in Fig. 1, looking in the direction of the arrows;

Fig. 3, a fragment, drawn to an enlarged scale of the section on the line 3—3 in Fig. 4 70 looking from above; and, Fig. 4, a fragmentary longitudinal vertical section on the line 4—4 in Fig. 1.

Similar parts are designated by similar numerals.

Referring to the drawings, 10 represents a portion of the inclosing shell of the stove, the lower part of which is in the form of the frustum of an inverted cone (Fig. 2), though the entire shell is preferably made 80 of one continuous sheet of metal and which is formed as will be described farther on. A cast iron fire pot 11, which may be supported in the usual way, is located in the lower part of the shell 10 the walls of each 85 being spaced apart from the other by the flange or lip 12 on the upper edge of the fire pot. The expansion chamber 13 has the general shape of the carpel of an orange, the ends of the carpel being brought toward 90 each other to a limited extent, so that the line of intersection 14, of the meridian planes thereof, and consequently the meridian planes also, will be arched upwardly as shown in Fig. 2, and backwardly as shown 95 in Fig. 1. The meridian planes thus distorted are represented by the upper, continuous, inclined wall 15 and by the lower inclined wall or hood 16, the latter having any suitable perforations or apertures 17. The draft 100 inlet-chamber 18 may project from the fire pot 11, the chamber 18 communicating downwardly with the space 20 between the shell 10 and the fire pot 11. The draft of air passes

into the chamber 18 through an opening in its front and may be controlled by any suitable means, for instance, the rotary door 21, which is in common use.

5 Below the line 22—22 in Figs. 2 and 4, the shell 10 and the fire pot 11 are each corrugated and are so arranged that the corrugations in the one will register as nearly as possible with the corrugations in the other 10 for the purpose of making the space 20 uniform in extent between the opposing surfaces of the shell 10 and the fire pot 11. The corrugations taper from a maximum 15 at the lowest parts of the shell and the fire pot, to nothing at about the level of the line 22—22, as indicated in Figs. 2 and 4, the relative arrangement of the corrugations being shown by Fig. 3.

I am aware that others have used corrugated stove bodies to increase the radiating 20 surface and have tapered the lower part of the bodies in order to radiate the heat downwardly onto the floor and I am also aware that corrugated fire pots have been used 25 heretofore, but I do not know of any instance where anyone has anticipated my construction, namely, that of having the fire pot and the surrounding body or shell corrugated to correspond to each other in 30 the manner described, in order that their opposing faces may be everywhere approximately equidistant from each other, thus allowing a current of heated air to flow 35 through the space between them in a smooth steady stream. Were either of the surfaces perfectly smooth and only the opposing surface corrugated, which has, so far as I know, always been the case heretofore, then a current of heated air flowing between these 40 surfaces, would be subjected to a peculiar pulsating effect caused by the alternately contracted and expanded space through which the heated air would be compelled to flow and consequently be greatly impeded. 45 In using my improved stove, the air draft is admitted into the inlet chamber 18 as shown by the arrows, (Fig 4) then flows downwardly into the space 20 around each side of the fire pot 11, by which the air is 50 heated, and most of it caused to press upwardly, close against the under side of the lip 12 until it reaches the rear of the stove and flows into the expansion chamber 13, which latter by its peculiar shape allows a 55 graduated expansion to the stream of heated air, the reaction of which against the back of the chamber forces the stream forward while the inclined and arched wall 15 deflects it so it will flow through the ports 17 60 into the fire.

The special object of the expansion chamber is to provide an even flow of superheated air to the surface of the fire, thereby burning gases which ordinarily escape through 65 the chimney.

Having fully described my invention, what I claim is:

1. In a stove having a fire pot, a surrounding shell spaced apart therefrom, and a suitably located draft inlet, the combination therewith, of a chambered portion having the general shape of the carpel of an orange lying crosswise the top of the fire pot in a position opposite the said draft inlet, the said chambered portion formed by 70 an apertured bottom wall intersected by a solid top wall and making an acute angle therewith, the space included between the said intersecting walls opening directly into the space included between the said 75 fire pot and the said surrounding shell, for the purpose specified.

2. In a stove having a fire pot, a surrounding shell spaced apart therefrom and a suitably located draft inlet, the combination 80 therewith, of an apertured hood surmounting a portion of the said fire pot, and located diametrically opposed to the said draft inlet, the said hood sloping upwardly toward the center of the stove and at a suitable distance from the said center intersecting a superposed solid wall inclined away from the center of the stove, the space included between the said hood and the said 90 wall opening directly into the space included 95 between the said fire pot and the said surrounding shell, for the purpose specified.

3. In a stove comprising a fire pot a surrounding shell spaced apart therefrom and a draft inlet located in the front of the 100 said surrounding shell, the combination with the said fire pot of an apertured, suitably curved hood extending over the rear upper portion thereof, and an upwardly sloping solid wall intersecting the said hood and 105 having a curved edge for bearing against the interior of the said surrounding shell in such a manner that a space having the general shape of the carpel of an orange will be formed between the said hood and the said sloping wall, this space being in direct communication with the space included 110 between the said fire pot and the said shell, for the purpose specified.

4. In a stove, the combination with a fire 115 pot having tapering corrugations, of a surrounding shell having corrugations corresponding to, and registering with, the tapering corrugations of the said fire pot, the fire pot and the shell being suitably spaced 120 apart for the purpose specified.

5. In a stove, the combination with a fire pot having tapering corrugations, of a surrounding shell having corrugations corresponding to, and registering with, the tapering corrugations of the said fire pot, the fire pot and the shell being suitably spaced apart from each other; a draft inlet leading into the space included between the fire pot and the shell; a suitably shaped expansion cham- 125 130

ber communicating with the said included space and with the interior of the said fire pot; and an inclined apertured wall, all suitably located, for deflecting a current of air from the said expansion chamber downwardly into the said fire pot for the purpose specified.

In testimony whereof I affix my signature in presence of two witnesses.

ROBERT F. CLARK.
